FASTENER

Frank Headon, New York, N. Y.

Application September 2, 1943, Serial No. 500,899

5 Claims.

(Cl. 24—245)

The present invention relates to a clasp or fastener adapted for use in holding fabric and the like and more particularly in supporting thin hose or stockings.

An object of the invention is to provide a novel and advantageous device which is very effective for the purpose specified.

Another object is to provide a simple form of clasp adapted for use with very thin fabrics without any substantial tendency to damage the same.

Another object is to provide a device of the character specified which is very simple of construction and economical to manufacture.

Another object is to provide an advantageous form of clasp by which undue stretching of the clasped fabric is avoided during both the clasping and unclasping operations.

A further object is to provide a simple and effective clasp in which the clasping and unclasping is rendered possible by the resiliency of the parts.

In carrying out the invention in a preferred manner, use may be made of two substantially thin members or plates of resilient material, such as a suitable plastic material which is resilient in its finished form. These plates may be supported in any suitable manner as by tapes or the like attached thereto, and may be curved, especially the inner one, to conform to the surface of the leg or other part of the body engaged thereby. Also the clasp may be so thin as not to be noticeable through outer garments. Flexibility of the plates at any desired location may be increased by decreasing the amount of material at such location, as by reducing the thickness of the plates.

The outer plate may have a longitudinal opening, orifice or slot with rounded ends and the inner plate or member may have at its outer face a projection which may fit closely in the opening of the outer plate or member and extend to the outer face thereof. The outer plate may be placed over the fabric to be clamped on the rear plate and may be secured by flexing it to a straighter shape so that parts thereof may be placed over edges of coacting parts on the rear plate, and then releasing it so that the coacting parts will engage each other and hold until released by another flexing of the outer plate.

Other objects, features and advantages will be apparent upon consideration of the following detailed description and of the drawing in which

Fig. 1 is a front elevation of a device embodying the present invention;

Fig. 2 is a view of the device of Fig. 1, as seen from below;

Fig. 3 is a view of the device of Fig. 1 as seen from the right;

Fig. 4 is a front elevation of the front plate of the device;

Fig. 5 is a front elevation of the rear plate; and

Fig. 6 is a section taken along the line 6—6 of Fig. 1.

10 Referring to the drawing, the illustrated form of the clasp or fastener comprises a rear plate 10 and a front plate 11 provided with an elongated opening or slot 12 adapted to be filled by a projection 13 forming a part of the front of the rear plate 10. Fabric 14 (Fig. 5) positioned between the plates 10 and 11 and clamped therebetween, will be strongly held against movement in its own general plane.

The members or plates 10 and 11 may be 20 clamped together with fabric therebetween by having the ends 15 of the slot 12 so spaced as to grip the ends of the projection 13 of the rear plate 10 when forced thereover. However, there may also be provision for clamping the plates 10 and 11 by engagement of inwardly facing shoulders 16 on the rear face of the front plate 11 with outwardly facing shoulders 17 which may be the end surfaces of the rear plate 10.

The closing of the clasp or fastener on fabrics 30 of an article such as a stocking, may be effected by pressing the plates 10 and 11 together near the middle thereof. This action will flex the front or outer plate 11 and cause it to straighten so that the shoulders or ends 15 of the slot 12 will 35 pass over the outer ends of the projection 13 and then grip the same when the outer plate is released to assume its normal shape. Clamping of the ends 17 of the inner or rear plate 10 by the shoulders 16 at the rear or inner face of front 40 plate 11 may be effected in the same way. Release of the clamp may readily be effected by placing the fingers at the rear of the ends of the front plate 11, and pressing the thumbs against the projection 13 of the rear plate 10, thus flexing 45 the outer plate to disengage it from the rear plate. As indicated in Figs. 2 and 6, the plates 10 and 11 are normally locked together because the shoulders 15 and 16 extend under the ends 16 and 17 respectively.

50 The plates or members 10 and 11 may be supported from a garment (not shown) in any suitable manner as by tapes, either elastic or inelastic. To this end the rear plate may be provided at its upper edge and near opposite ends thereof 55 with slots 18 for attachment of tapes or the like.

For the same purpose the front plate 11 may be provided with a single slot 19 to receive a supporting tape. Obviously the arrangements for supporting the plates 10 and 11 may be varied.

Obviously it would be feasible, without departing from the invention, to change the shapes of the opening 12 and of the projection 13 and to change the shoulders 16 and ends 17 from straight edges to other suitable shapes.

Although the fastener is particularly adapted for attachment to a stocking, it may be used to hold a tape or tapes positioned transversely or longitudinally with respect to the plates, or to hold crossed tapes at their crossing.

It should also be understood that instead of a single opening in one plate and a single projection on the other plate, there might be a plurality of openings with a corresponding number of projections to enter them.

It should be understood that flexing of the front plate 11 in engaging or disengaging the plates may be accompanied by a corresponding flexing of the rear plate 10.

The clasps of the present invention may also be used for ornamental purposes, as in clips for the hair or apparel. For such purposes the plate 11 might be increased in size to provide more space for ornamentation.

It should be understood that various changes may be made and that various features may be used without others, without departing from the true spirit and scope of the invention.

Having thus described my invention, I claim:

1. A clasp comprising a plate having a convex face with a projection of which the edge consti-

tutes a shoulder with oppositely facing undercut portions in a direction of curvature of said face, and a resilient plate having a face to cooperate with said convex face in clamping fabric and the like therebetween and provided with an opening having slightly larger dimensions than those of the projection to receive and hold said projection and fabric thereon.

2. The combination as set forth in claim 1 in which the plate containing the opening is provided at opposite ends of its fabric engaging face with projections providing opposed shoulders for locking engagement with the ends of the projection-carrying plate.

3. A clasp comprising a plate having a longitudinally convex face with projecting means providing oppositely facing undercut shoulders in such longitudinal direction of curvature, and a curved resilient plate having a concave face to cooperate with said convex face in clamping fabric and the like therebetween and provided with an opening having slightly larger dimensions than those of the projecting means to receive and hold said projecting means and fabric thereon.

4. The combination as set forth in claim 3 in which each of the fabric-clasping plates is provided with means for supporting the same.

5. The combination as set forth in claim 3 in which the plate containing the opening is provided at opposite ends of its fabric engaging face with projections providing opposed shoulders for locking engagement with the ends of the plate carrying the projecting means.

FRANK HEADON.
